KNOCKDOWN CHEST OF DRAWERS

Harry Derman, Laurelton, N. Y.

Application July 14, 1939, Serial No. 284,421

8 Claims. (Cl. 312—144)

This invention relates to what is commonly referred to as a chest of drawers, or in other words, a cabinet having a series of vertically spaced drawers for the storage of various articles; and the object of my invention is to provide a device of the character described which is so constructed as to provide the collapsing or knocking down of the entire device for the packing and shipment thereof in a relatively thin package substantially of the width governed by the width of the resulting chest or cabinet, and also of a length substantially equal to the height thereof; a still further object being to provide a knock-down structure of the cabinet described consisting of a wooden skeleton frame forming guide supports and spacing means for the respective drawers employed and upon which is arranged a single sheet of paper or corrugated board to form back and side walls of the resulting chest or cabinet; and further to the inclusion of a top wall member forming a closure for the top of the cabinet; a still further object being to provide a plurality of drawers each composed of a single collapsible sheet of material with means supporting the sheet in extended position in forming the drawer; a still further object being to provide means for reinforcing the front corner portions of the frame intermediate adjacent drawers to maintain fixed relationship and sizing of the drawer receiving openings at the front of the cabinet; a still further object being to provide a structure wherein part of the skeleton frame of the cabinet is foldably and collapsibly coupled with respect to the back wall member of the cabinet in maintaining predetermined relationship with respect thereto; and with these and other objects in view, the invention consists in a device of the class and for the purpose specified which is simple in construction, efficient in use, and which is constructed as hereinafter described and claimed.

The invention is fully disclosed in the following specification, of which the accompanying drawings form a part, in which the separate parts of my invention are designated by suitable reference characters in each of the views, and in which:

Fig. 1 is a front view of a chest or cabinet made according to my invention.

Fig. 2 is a perspective view showing the exploded arrangement of the respective chest or cabinet parts, and indicating only one of the drawer members employed.

Fig. 3 is a sectional detail view of one corner portion of the chest.

Fig. 4 is a perspective view of one inner corner portion of the frame showing one of the reinforcing members which is employed.

Fig. 5 is an enlarged sectional view of one rear corner portion of the cabinet showing a slight modification; and,

Fig. 6 is an inside view of part of the back of the cabinet showing the arrangement of frame parts thereon in accordance with the teachings in Fig. 5.

In the construction of chests of drawers and similar cabinets or containers of the type and kind commonly composed of paper reinforced by wood strips or frame parts, it has been the common practice to construct a complete cabinet wherein the various wall parts, drawers, and the like, are fixedly secured in an extended position, thus necessitating the packing and shipping of the chests or cabinets in their set up condition, the result of which has brought about a large expense in the cost of handling and transportation of the products by reason of the excessive amount of room occupied thereby and the limited number of light products that can be stored and packed in a freight car, truck, or other means of transportation. Still further, objection has been raised to the conventional type of device of this kind by reason of the damage caused thereto in the shipment and handling thereof, notwithstanding the care taken in packing the assembled chests in corrugated or other protective containers. Many of these cabinets are comparatively large in construction and are bulky and awkward to handle even though the weight thereof is not sufficient to mention. It is the purpose of my invention to so construct a chest or cabinet of the type and kind under consideration as to provide independent parts which are readily attachable and detachable to provide a quick setting up of the device as well as the quick disassemblage of the device for shipment and transportation thereof.

It will, of course be understood that the invention is applicable for the construction of chests or cabinets of many types and kinds with different arrangements of drawers, and of different external shapes. However, in the accompanying drawings, I have shown to illustrate one adaptation of my invention, a simple and more or less conventional form of cabinet or chest of drawers.

In Fig. 1 of the drawings I have shown at 10 a cabinet consisting of a front frame part 11 of rectangular cross-sectional form; that is to say, comprising grooved side rails 12, a grooved top

rail 13, a series of vertically spaced drawer partitioning bars 14, the ends of which have a tongue and groove or other fixed mounting in the rails 12. This mounting is further reinforced by angle-iron plates 15, note Fig. 4, arranged upon the inner surfaces of the rails 12 with a part 16 extending into the groove or channel 12a of the rail, with the other part 17 arranged upon the inner surface of the rail 12, and including centrally thereof a long attaching plate 18 through which nails or other fastening devices 19 are passed into the bars 14. The reinforcing plates 15 serve to strengthen the mounting of the bars and also to prevent spreading of the rails, thus maintaining substantially positive rectangular contour of the drawer receiving openings 20 formed in the frame 11; five of these openings being shown in the present construction to receive five similar drawers 21.

The bottom bar 14 also forms the bottom cross rail of the frame, the lower ends of the rails 12 protruding to form supporting feet 22 which are reinforced by corner braces 23. The upper surfaces only of the bars 14 are provided adjacent the reinforcing plates 15 with substantially dovetailed sockets 24, for receiving dovetailed couplings 25 at the forward end of drawer supporting rails 26. These rails are made up in two unit parts which are fixedly joined or secured to a vertical frame part or riser 27. In other words, risers 27, with the five rails 26 attached thereto, form similar additional parts of the knockdown structure. The rails 26 are readily attachable and detachable with the bars 14 by simply dropping the same into the sockets 24 or moving the same upwardly therefrom.

Another of the cabinet unit parts comprises a sheet 28 of cardboard, corrugated board, or the like, treated, coated or otherwise prepared at least on the outer surface thereof to give any desired ornamental effect. This sheet is simply scored and folded to form a back wall 29, and two similar side walls 30, the forward edges of which are adapted to fit snugly in the groove 12a of the rails 12 in assembling the device. Suitable fastening devices are provided to retain the walls in connection with the rails 12, and should preferably be of a type such as upholstery tacks, which can be readily removed, and especially when the further transportation of the device is contemplated.

The lower edges of the side walls 30 are also preferably reinforced by channel strips 31 secured thereto, and the lower surfaces of these strips will be arranged in alignment with the lower ends of the feet 22 when the cabinet is completely assembled. This will support the lower edge of the back wall as well as the surface on which the cabinet is arranged, but it is here to be understood that the lower ends 27a of the rails 27 protrude sufficiently to form supporting feet to support the cabinet at the rear thereof. The upper ends 27b of said rails fit snugly upon the top wall part 32 of the cabinet, which part is readily attachable and detachable with respect to the upper edges of the back and side walls 29 and 30. The top wall has downwardly extending channel strips 33 at the rear and side edges thereof for engaging the upper edges of the back and side wall parts. The top wall proper comprises a sheet of cardboard or corrugated board, the forward edge 34 of which protrudes beyond the strips 33 to enter a groove 13a formed in the top rail 13 of the frame 11. Here again, suitable fastening devices may be used in

securing the forward edge 34 to the rail 13, and also in securing the flange strips 33 to the upper edges of the back and side walls.

As previously stated, each drawer 21 is of the same size and in like manner of the same construction. As these drawers form the subject matter of a companion application filed of equal date herewith, detailed reference to these drawers will be omitted except in disclosing that the drawers are composed from a single sheet of cardboard or corrugated board cut and scored to form a bottom wall 35, upwardly foldable front and rear walls 36, 37. The upwardly foldable side walls 38 have their corner portions reinforced by integral flaps 39 and channelled fastening strips 40 are disposed upon the upper edges of the front and back walls and interlock with corner flanges as at 39 in holding the drawer wall parts together, suitable means, such as tacks, being provided for retaining the wall parts against displacement from the strips at the corner portions thereof.

With this construction, the outer surfaces of the wall parts of the drawer may be coated or otherwise characterized to that employed on the outer surfaces of the walls 29 and 30, or may be contrasting thereto, depending entirely upon the effect which is desired. It is also preferred that handle members in the form of wooden blocks 41 be attached centrally of the outer walls 36 of the drawer members to facilitate convenient movement of the drawer members forwardly and backwardly in the cabinet or chest.

With the construction as shown in Figs. 1 to 4 inclusive, it will be understood that the several parts will be knocked down and collapsed into a relatively thin package of a width substantially similar to the width of the frame 11, and a height substantially similar thereto, and a thickness represented by the collapsed and knocked down parts arranged one upon the other. It will be understood that the rails 40 are detached from the drawer parts, and at least two of the walls of the drawer part blanks are foldable upon the bottom wall 35, with the other walls extending in the plane thereof.

In setting this cabinet up for use, the rails 26 are first coupled with the bars 24 which forms a more or less rectangular skeleton frame as illustrated in Fig. 2 of the drawings, after which the back and side walls are moved around this skeleton frame with the strips 31 thereon; the forward edges of the side walls being secured to the rails 12, after which the separate drawer members 21 are assembled and then placed in the drawer receiving openings 20 and tested for free action in each of the openings 21 and over the rails 26, after which the top wall 32 is secured in position, and if desired, the uppermost drawer may be removed for this purpose. It will, of course, be understood that the inner or rear walls 37 of the drawers, or the strip 40 thereon, will strike the forward surfaces of the rails 27 in limiting the inward movement of the drawers thus relieving any strain upon the back wall 29 proper of the cabinet. The front strip 40 may be colored or coated to correspond with and match the coating applied to the rails or bars of the frame 11; whereas the rails 26 and 27 need not be coated for decorative purposes, as they are entirely concealed within the cabinet when the doors are in closed position.

Instead of arranging and assembling the parts as above described, it is also within the spirit of my invention to first hingedly attach the rails

21 to the inner surfaces of the back wall 29 of the cabinet by simply employing strong flexible fabric hinges 42 which are secured to the inner surface of the wall 29 and to the surface of the rails 21 so as to allow the rails to swing upon the inner surface of the back wall 29 in the manner illustrated in part in dotted lines in Fig. 5 of the drawings, and as shown in full lines in Fig. 6 of the drawings, in which figure it will be noted that the rails 26 nest one above the other; there being sufficient flexure therein to accomplish this result notwithstanding the same alinement of the attached ends of the rails 26 to the rails or risers 27. In this way, both unit parts 26, 27 will be definitely located with respect to the wall 29, and will be foldable or collapsible with respect to the unit 28, thus eliminating the necessity of independently handling these parts.

In assemblage, it will be apparent that the side walls 30 are extended outwardly in moving the drawer guiding rails forwardly for attachment to the bars 14, after which the side walls 30 will be moved into the grooves 12a. On the other hand, the forward edges of the side walls 30 may be first coupled with the rails 12, with the rails 26 resting upon the upper surfaces of the bars 14, after which these rails may be set in the dovetailed grooves 24 of said rails.

By constructing a cabinet of the type and kind under consideration in the manner described, in addition to providing a stronger and more durable cabinet of the type under consideration and in the saving of usual labor costs on the parts of the manufacturer in assembling the cabinet, another tremendous saving is effected in the ability of a manufacturer to ship a greater number of the cabinets or chests in a car or truck for transporting the same. Furthermore, a material saving is effected in the storage space required for the storage of manufactured products. Beyond these advantageous features, it is also to be borne in mind that the more compact package facilitates the more convenient handling thereof and eliminates breakage or other destruction to the product, this being commonly experienced in the sale of completely assembled products of this type and kind.

It will readily appear that by spacing the bars 14 differently in the frame 11, drawers of different heights may be provided, the arrangement of the rails 26 on the risers 27 being correspondingly arranged; and the set of drawers 21 employed will be made of corresponding sizes. It will also be understood that the rails 27 may be secured to the back wall 29 in the structure as shown in Figs. 1 to 4 inclusive, although I have found from experience that the snug engagement of the wall 29 with the risers 27 is sufficient to maintain the parts in proper position.

The drawers 21 will be made to fit snugly between the rails 12, but will have slight clearance with the inner surfaces of the side walls 30, these walls being sufficiently close, however, to guide the drawers in their sliding movement within the cabinet.

Having fully described my invention, what I claim as new and desire to secure by Letters Patent is:

1. A chest of drawers of the class described, comprising a plurality of independent skeleton and fiber board parts, said parts being collapsible into a thin knockdown package and when assembled forming a chest having back, side and top wall parts with a skeleton frame forming part of said chest, said skeleton frame comprising a

front frame part dividing the front of the chest into drawer receiving openings and supporting forward edges of the side and top wall parts, and other inner frames detachably connected with the front frame and extending between said front frame and the back wall of the chest to divide the chest into vertically spaced drawer receiving and supporting compartments.

2. A cabinet structure for knockdown chest of drawers of the class described, said cabinet comprising detachably and collapsibly related parts, one part comprising a front skeleton frame having vertical side rails joined by vertically spaced horizontal cross bars, another part comprising a single sheet of material folded to form back and side wall parts, forward edges of the side wall parts being detachably coupled with the vertical rails of said skeleton frame, a top wall part having depending back and side flanges engaging the upper edges of the back and side walls of the second named part, two other skeleton frames arranged between the back wall and the front skeleton frame, and said last named frames having horizontal rails detachable from and arranged in alinement with the cross bars of the front skeleton frame.

3. A knockdown chest of drawers composed of wood skeleton frame parts, paper board back, side and top wall parts, all of said parts being detachable and collapsible for compact packing, the wood skeleton frame parts comprising a front frame unit having a series of drawer openings and two similar drawer supporting and guiding frames detachably coupled with respect to the front frame unit, the back and side wall part comprising a unitary sheet folded at the intersections of the back and side walls, the top wall having depending flanges engaging upper edge portions of the back and side walls, and the forward edges of the side and top walls engaging the front frame unit in the assemblage of the chest with the back wall engaging said drawer supporting and guiding frames.

4. A knockdown chest of drawers of the class described comprising a plurality of detachably coupled unit chest parts, said parts comprising a front skeleton frame having side rails and vertically spaced cross rails forming within the frame a series of vertically spaced drawer receiving openings, two similar reinforcing and drawer supporting frames each comprising vertical rear rails and forwardly extending drawer supporting rails detachable from the cross rails of the front frame, a single sheet of scored and folded material forming back and side walls of the chest, the side walls being detachable from the side rails of the front frame with the back wall engaging the vertical rails of the drawer supporting frames, and a top wall having depending back and side flanges engaging upper edges of the back and side walls with the forward edge of the top wall engaging the uppermost cross rail of the front frame when the chest is in set-up condition.

5. A knockdown chest of drawers of the class described comprising a plurality of detachably coupled unit chest parts, said parts comprising a front skeleton frame having side rails and vertically spaced cross rails forming within the frame a series of vertically spaced drawer receiving openings, two similar reinforcing and drawer supporting frames each comprising vertical rear rails and forwardly extending drawer supporting rails detachable from the cross rails of the front frame, a single sheet of scored and

folded material forming back and side walls of the chest, the side walls being detachable from the side rails of the front frame with the back wall engaging the vertical rails of the drawer supporting frames, a top wall having depending back and side flanges engaging upper edges of the back and side walls with the forward edge of the top wall engaging the uppermost cross rail of the front frame when the chest is in set-up condition, and means hingedly supporting the vertical rails of the reinforcing and drawer supporting frames upon the inner surface of the back wall of the chest.

6. A knockdown chest of drawers of the class described comprising a plurality of detachably coupled unit chest parts, said parts comprising a front skeleton frame having side rails and vertically spaced cross rails forming within the frame a series of vertically spaced drawer receiving openings, two similar reinforcing and drawer supporting frames each comprising vertical rear rails and forwardly extending drawer supporting rails detachable from the cross rails of the front frame, a single sheet of scored and folded material forming back and side walls of the chest, the side walls being detachable from the side rails of the front frame with the back wall engaging the vertical rails of the drawer supporting frames, a top wall having depending back and side flanges engaging upper edges of the back and side walls with the forward edge of the top wall engaging the uppermost cross rail of the front frame when the chest is in set-up condition, and means comprising angle-iron plates for reinforcing the front frame where the cross bars join the vertical side rails.

7. In a knockdown chest of drawers of the class described comprising a cabinet composed of detachably and collapsibly related parts forming when assembled a plurality of drawer receiving compartments, one part of the cabinet comprising a sheet folded to form back and side wall members, a front frame secured to the side wall members of the first part, said frame having vertically spaced rails forming the drawer compartments of the cabinet, a top part secured to the frame and upper edges of the back and side walls, two other frame parts hingedly supported on the inner surface of the back wall part and collapsible flatly thereon in the collapsed position of the wall members, and said frame parts comprising a plurality of vertically spaced rails extending forwardly in the cabinet detachable from the rails of the front frame to form drawer guiding and supporting members.

8. In a knockdown chest of drawers employing detachably and collapsibly related back and side wall and top wall parts, a reinforcing and partitioning skeleton frame detachable with respect to said parts, said skeleton frame comprising a front frame part having vertical side rails joined by vertically spaced horizontal rails, and two similar drawer supporting frames comprising vertical back rails and forwardly extending horizontal rails, and means detachably coupling the horizontal rails of the drawer supporting frame parts with corresponding rails of the first named frame part adjacent the vertical rails thereof.

HARRY DERMAN.
